APPARATUS FOR PRODUCING GRINDING
WHEELS

Walter S. Rae, Pittsburgh, Pa.

Application June 16, 1932, Serial No. 617,681

6 Claims. (Cl. 154—1)

Generically this invention relates to machines for winding fibrous material such as thread and the like on suitable cones or cores, but it more especially is directed to the type adapted to simultaneously impregnate the thread and the body being formed, with an abrasive substance during the winding operation, whereby the production of abrasive bodies such as grindstones and the like are effected.

One of the principal objects of this invention is the provision of a method and apparatus of the above character, including an adjustable pressure means for forming the thread or other fibrous material as it is being wound into the desired shape, and comprising flange elements or disks relatively movable with respect to each other and adapted to be locked in the desired position, whereby the size and shape of the abrasive body or grinding stone may be varied as desired.

An important object of this invention is the provision of means for continuously applying an abrasive substance to the body being formed and the thread as it is wound thereon, and pressure or tamping shoe means for simultaneously forcing the abrasive and impregnated thread into the progressive surface of said body, and maintaining the relative position of said pressure means constant with respect to the surface of said body during its building up process, said tamping means being operable to regulate the degree of hardness and density of said abrasive body as desired.

Another important object of this invention is the provision of a method and apparatus of the above character for producing abrasive bodies such as grindstones and the like, including what may be termed a comb mechanism for directing a strand or a number of strands of fibrous material to the body being formed, and playing such strand or strands from side to side over the surface of such body during its rotative course of being built up, said surface at every stage of the body forming process presenting a woven-like effect, said mechanism being operable to vary the spaced relation of the respective strands and change the weaving pattern to vary the density of said body by presenting a closely or loosely woven structure as desired, the weaving movement of said mechanism being variable in accordance with differing surface areas of said bodies as desired.

With these and other objects in view, which will become apparent as the description proceeds, the invention resides in the construction, combi-

nation, and arrangement of parts, hereinafter more fully described and claimed, and illustrated in the accompanying drawings, in which like characters of reference indicate like parts throughout the several figures, of which:

Fig. 1 is a front elevation of my improved device.

Fig. 2 is a side view of Fig. 1.

Fig. 3 is a top plan view partly in section taken on the line 3—3 of Fig. 1.

Fig. 4 is a fragmentary detail view partly in section of the winding and body forming mechanism and operating clutches.

Fig. 5 is a fragmentary detail view of the threader comb operating mechanism.

Fig. 6 is a fragmentary detail view of the adjustable threader comb supporting structure.

Fig. 7 is a section on the line 7—7 of Fig. 5.

Fig. 8 is a fragmentary detailed transverse section through the pressure mechanism, mounting, and lateral adjusting screw, with the driving screw in elevation.

Fig. 9 is a vertical section on the line 9—9 of Fig. 8.

Fig. 10 is a top plan view of the pressure bar clip.

Fig. 11 is a plan view of the eccentric lock element, and portion of operating handle, and

Fig. 12 is a transverse section of the completed grindstone.

The devices of this general character with which I am familiar have proven unsatisfactory by being too complex in structure, not readily adjustable to produce different sized abrasive bodies or grindstones, not exerting pressure against the entire surface area of the sides during the building up process, incapable of exerting pressure against the abrasive surface of the body during its building up process, such pressure mechanism receding as the diameter of the body increases,

and likewise incapable of expeditiously changing the weave or spaced relation of the strands of fibrous material wound to form the body, etc., and it was to overcome such deficiencies, and to provide a method and apparatus including novel

pressure body forming and shaping adjustable disk elements, an adjustable interchangeable shoe pressure mechanism and thread or strand controlling comb mechanism adjustable in accordance with bodies of varying surface areas adapted

to direct one or more strands to the device in a manner to maintain the surface of the body level during the winding and building up operation,

and capable of changing the spaced relation of said strands and varying the woven-like relation

thereof as desired, that I designed the device forming the subject matter of this invention.

In the illustrated embodiment characterizing this invention there is shown a compound fiber 5 and abrasive body forming machine A, adjustable pressure body forming mechanism B, thread control comb mechanism C, and adjustable pressure shoe mechanism D, and which insofar as practicable will be dealt with descriptively under 10 the above headings.

There is shown a supporting frame E comprising in the present instance four perpendicular angle beam standards 1 connected at their upper ends by cross bars 2 secured thereto by welding 15 or in any suitable manner. Spaced from their lower ends said corner posts or standards are similarly connected by cross bars 3 on which is supported the table top or platform 4 formed with an opening 5 and extending rearwardly beyond 20 standards 1 and with its free edge supported by angle brace members 6 bolted or otherwise secured thereto and to said standard 1. At their lower ends the front standards are similarly connected by cross bars 7 and similar bars may extend across the ends if desired. The bars 7 are 25 suitably supported on beams or foot like supports 8 adapted to support the frame structure spaced from the floor as desired.

A substantially rectangular frame section 30 adapted to support the pressure shoe mechanism D and its operating components is positioned adjacent frame E with one side projecting beneath the free edge of platform 4 comprising upright standards 9, connected at their upper ends by 35 side bars 10 and at their lower ends by side bars 11 and end supporting beams 12 in turn supported on bars or feet 8 similar to frame A. One of the side bars 10 is connected to the platform 4 by brace members 13 bolted or otherwise suitably secured as desired.

Suitably mounted on supporting beams 14 is a power unit or motor 15 having a driving shaft 16 carrying sprockets 17 and 18. Sprocket 17 is connected by chain 19 passing through opening 45 5 with sprocket 20 mounted on shaft 21 of the speed reducing mechanism 22 (standard type) suitably connected to shaft 23 of the pressure body shaping mechanism now to be described.

50 Pressure body shaping mechanism

The pressure body shaping mechanism B comprises drive shaft 23 mounted at its ends in bearing blocks 24 suitably secured on supporting pedestals 25 supported on beam sections or foot elements 26 similar to elements 8 heretofore described. Said shaft 23 is also mounted in bearing standards 26 suitably secured to the cross beams 3, and spaced inwardly from standard 26 suitably secured to platform 4 are clutch bearing 60 supports 27 and clutch assemblies 28. Secured to platform 4 adjacent supports 27 in any suitable manner are lugs 29 on which are hingedly mounted clutch operating handle elements 30 loosely connected to the complementary slidable clutch members 31 by means of which the driving section 23' of shaft 23 is operatively connected to the end sections of said shaft 23 on which are mounted the cone or core elements 32 on which the thread or fibrous material 33 is adapted to be wound in process of forming the desired body or grindstone F, as will hereafter more fully appear. Mounted on said end sections of shaft 23 adjacent the inner edges of the respective cores 32 are the pressure disks or plates 34 keyed or suitably 70 locked on said shaft, and mounted on said shaft 75

adjacent the outer edges of said cores are the similarly shaped complementary disks 35, relatively movable with respect to said disks 34 to accommodate different sized cores 32 according to the desired size of the body F being formed. Said disks 35 are adapted to be locked in the desired adjusted position by lock nut 36 threadedly mounted on said shaft or other suitable locking means. It is thus apparent that as the thread 33 is wound on the cone or cores 32 and as the body F is built up the disks 34 and 35 will exert pressure against the sides, shaping the same, and effecting therewith a unitary structure during the building up operation as will directly more fully appear.

10 Thread control comb mechanism

In order to properly direct the thread and the like to the shaping disks 34 and 35, and shiftingly distribute it over the surface of the body being formed on the respective cores 32, I employ the thread control comb mechanism C now to be described.

A plate 37 is attached to the face of each of the front standards 1 by welding or in any other suitable manner at points spaced above the table or platform 4 and of wider dimensions than said standards. A plate 38 is adapted to slidably seat on plate 37 attached thereto by cleat elements 39 secured by screws 40 or in any suitable manner. Said plate is formed at its upper edge with a lateral projection 41 through which extends screw bolt 42 threadedly engageable with lug 43 and squared at its upper end or otherwise formed to engage a suitable wrench for operating said screw to raise and lower said plate 38 as desired.

Secured to the face of plate 38 by bolts 44 spaced from its upper edge are a pair of bearing plates 45 in which is slidably mounted the toothed rack bar 46 formed with a slot 47 engageable with a suitable lug or the like limiting the slideable movement of the bar, and substantially central of the plate adjacent each side secured by bolts 44 is a bearing plate 48 formed with spaced apertured ears or lugs 49 between which is mounted by bolts 44 bearing blocks 50 in which is slidably mounted the thread control toothed rack bar 51 formed with key element 52 engageable in suitable slots in lugs 49 and block 50 to prevent rotation of said bar as will directly more fully appear.

Intermediate said rack bars 46 and 51 is an arm 53 welded or suitably secured at one end to plate 38 and having suitably mounted at its free end on bolt 54 idler pinion wheel 55 engageable in the teeth of said rack bars 46 and 51. One end of rack bar 51 is rounded as at 56 and suitably secured to the opposite end is arm 57 to the free end of which is suitably secured one end of cable 58 adapted to travel over pulley 59, and to the other end of which is attached counter weight 60 which is adapted to normally maintain rack bar 51 in retracted position. Said pulley 59 is mounted in bracket 61 secured by bolts 62 to frame standard 1.

The rack bar 51 is formed by welding or otherwise adjacent one end with projection 63 terminating in apertured lug 64 to which is adjustably secured by bolt 65 one end of slotted link 66; the other end is similarly secured by bolt 67 to one end of slotted link 68 and to which a similarly slotted link 69 is adjustably secured by bolt 70. Link 69 terminates at one end in the thread control comb member 71 formed with suitable tines or apertures through which the re-

spective threads 33 are directed to the winding core 32 as hereinbefore described. The above described link structure permits adjustment of said comb with respect to the winding cores 32 and disks 34 and 35 and different sized bodies F formed thereby, as desired.

Positioned intermediate the rack bars 51 and in alignment therewith are the twin shafts 72 mounted at their outer ends in bearings 73 suitably secured and supported on, in the present instance, angle supports 74 bolted or otherwise secured to the platform 4 and with their meeting ends journaled in bearings 75 suitably secured to the central T-shaped support 76 attached to the platform 4 as desired. Keyed or otherwise locked to said shaft intermediate bearings 73 and 75 are the respective reduction pulley assemblies 77, and similarly locked on the outer ends of shafts 72 are the inclined rack operating disks 78, the rotation of which in contact with the rounded ends 56 causes the reciprocation of said rack bars 51 and combs 71 as hereinbefore explained.

In this connection it is necessary to vary the reciprocal movement of the combs 71 in accordance with the width of the bodies F being formed and which is accomplished by eccentrically adjusting the longitudinal axis of rack bar 51 with the axis of rotation of disk 78. For instance, operation of screw 42 in one direction raises plate 38 offsetting rack bar 51 with respect to the axis of rotation of disk 78 and increases the reciprocating movement of comb 71, and the lowering of said plate decreases said movement as will be clear without further discussion.

The manner of driving said comb operating mechanism may be described as follows: From sprocket 79 mounted on drive shaft section 23' sprocket chain 80 connecting the same with sprocket wheel 81 suitably secured centrally on shaft 82 journaled in hangers 83 bolted or otherwise secured to cross beams 84 suitably supported by frame members 1, and the reduction pulley assemblies 85 securely mounted on shaft 82 on opposite sides of sprocket 81, and in alignment with their respective complementary assemblies 77 and to which they are adjustably connected by the respective belts 86, as will be clear without further description.

It might be well before proceeding further to now describe the mixing units and manner of delivering the abrasive mixture to the respective thread winding mechanisms.

Mounted at the top on opposite sides of frame E in perpendicular alignment with the cores 32 and disk assemblies thereon are the abrasive material mixing boxes or containers 87 welded or bolted to frame members 2 and 84, and extending through and suitably journaled in said boxes is said shaft 88 also journaled in spaced bearings 89 suitably mounted on the intermediate cross beams 84' suitably connected to and supported by frame E. Keyed or otherwise mounted on said shaft 88 is sprocket wheel 90 in alignment with sprocket 91 secured on driving section 23' of shaft 23 to which is connected by sprocket chain 92 and by means of which shaft 88 is driven to operate the mixing mechanisms mounted in said boxes (not shown). It will thus be seen that the abrasive material in the boxes 87 is thoroughly mixed prior to its delivery through a suitable discharge opening 87' in the bottom thereof to the respective thread winding cores 32 and body shaping disks 34 and 35 by gravity or through suitable conduits if desired during operation of

the machine in process of building up the composite fiber and abrasive bodies F. The manner of acting on the abrasive material after it has left the boxes 87 and with respect to the impregnation of said body therewith by the pressure shoe mechanism D will be now described.

Pressure shoe mechanism

The pressure shoe mechanism D comprises a pair of rectangular bars 93 welded or otherwise suitably secured at their ends to the supporting blocks 94 supported on and suitably secured to frame members 10 in approximate alignment with the respective cores 32 and their disks 34 and 35. Mounted on each of the respective bars 93 is a slidable carrier block 95 formed with a cutout opening 96 adapted to receive said bar 93, said opening being closed by screw carrier member 97 secured to said block 95 by screw bolts 98. The carrier member 97 spaced inwardly from its edges is formed with depending spaced apertured flanges 99 through which is adapted to extend the driving screw 100 suitably journaled in supporting blocks 94 and terminating at one end in the shaft member 101 having sprocket wheel 102 mounted on its free end and keyed or otherwise suitably locked thereon.

Mounted on and connecting the free ends of flanges 98 is a bottom plate 103 secured by bolts 104 threadedly engageable in said flanges with their heads countersunk as at 105, and mounted on said bottom plate 103 is the eccentric lock member 106 centrally apertured to receive the hub section 107 of lock bolt 108 threadedly engageable in said plate 103, said lock plate is formed with operating handle 109 and with cam slots 110 adapted to receive the cam lugs 111 projecting through openings 112 in said bottom plate and formed on the complementary movable locking blocks 113 mounted intermediate flanges 98. Said blocks 113 are formed with the complementary hollowed out threaded portions 114 adapted to provide when the blocks are in locking position threaded engagement with the screw 100 by means of which block 95 and its connected parts are caused to slidably traverse bar 93 upon operation of said screw.

Operation of handle 109 causes lugs 111 to move in cam slots 110 thereby drawing the complementary locking blocks 113 toward each other and in operative threaded engagement with screw 100 as above described, and movement of said handle in the opposite direction removes said block from contact with said screw permitting carrier block 95 with its connected parts to be freely slidable with respect to bar 93, as will be clear without further explanation.

Carrier block 95 is formed with an opening 115 communicating with opening 116 in which is adapted to seat the adjusting screw sleeve element 117 formed with projection 118 adapted to extend within opening 115, said sleeve adapted to threadedly receive the adjusting screw 119 extending through opening 120 in carrier block 95.

Dovetail mortise slot 121 formed in block 95 is adapted to slidably receive the complementary tenon 122 formed on adjusting plate 123, said plate 123 is suitably formed with lugs 124 adapted to project in suitable openings 125 formed in the under surface of anchor pressure frame section 126 adapted to seat on said adjusting plate, as will directly more fully appear.

Threadedly anchored in said plate 123 on opposite sides of pressure anchor bar 127 are the

stud bolts 128, and engageable over said pressure anchor frame 126 is a clip plate 129 apertured at one end to receive one of the bolts 128 to which it is rotatably secured by nut 130, and 5 it is formed at its opposite end with curved slot 131 by means of which it is detachably mounted to the opposite bolt 130 thereby firmly maintaining the pressure anchor frame 126 in operative position but permitting its ready removal or the 10 substitution of another interchangeable frame therefor as desired.

Adjacent the outer edge of block 95 adjusting screw 119 is formed with a reduced portion 132 adapted to extend through plate 133 secured to 15 adjusting plate 123 by screws 134. Mounted on said reduced portion 132 is bushing 135, and secured to the free end of said portion in seating engagement with said bushing secured by nut 136 is hand wheel 137, whereby said screw is 20 rotatably anchored to the adjusting plate 123 and operation of said hand wheel effects adjustment of said frame 126 transversely of bar 93, as will be clear without further description.

Said frame section 123 is substantially triangular in configuration, formed at its supporting 25 corner with a perpendicular section 138 and horizontal section 139 adapted to seatedly engage the adjusting plate 123 as hereinbefore described.

The inclined section 140 of said frame 126 is 30 adapted to form a seat for the substantially triangular shoe pressure bar frame section 141 connected thereto by anchor clip bolts 142, the two frames thus constituting a unitary pressure frame and anchor for the pressure plate member 143. 35 Said plate 143 is adapted to seat on the substantially perpendicular section 144 and is formed at its bottom with lug 145 adapted to engage a suitable opening or recess means not shown suitably connected to frame 141, and is formed at its 40 upper end with lug 146 adapted to seat under catch 147 formed on one end of member 148 hingedly mounted in ears 149, and is formed at its free end with lug 150 having mounted thereon spring 151 to normally maintain catch 149 in 45 anchoring engagement with pressure plate member 143. This plate 143 is adapted to be interchangeable with similar plates of different widths corresponding to the width of the particular body F being formed and the space to accommodate 50 such body between the pressure disks 34 and 35 as will be apparent. Likewise in connection with different dimensioned bodies F and, if desirable, at different stages of the building up process, the frame sections 141 and 126 may be respectively 55 interchangeable with similar frames of different dimensions to adjust and maintain proper relative positions of the bodies F and their pressure disks 34 and 35 with respect to the operatively positioned plate 143, and to coact with the body 60 F during its building up process to form a sump-like space 152 to catch the abrasive material G as it is delivered from the mixing box 87.

Coming now to the driving means and its supporting structure for the operation of screws 100 65 adapted to cause the respective pressure frames 126-141 with pressure plates 143 to recede as the diameter of the bodies F increase, the same comprises paralleled beams 153 suitably supported on side bar 10 with their inner ends extending 70 beneath platform 4 and their outer ends suitably connected to posts 154 welded or otherwise secured to side bar 11.

Sprocket chain 155 connects sprocket wheel 18 on motor shaft 16 with sprocket wheel 156 suitably mounted on shaft 157 journalled in bear-

ings 158 suitably secured to platform 4 and beam 153, respectively. Mounted on said shaft 157 spaced from one end is gear wheel 159 adapted to mesh with gear wheel 160 mounted on shaft 161 journalled in bearings 162 on opposite sides 5 of gear 160 suitably secured to the respective cross bars 163 supportingly connected to beams 153 in any well known manner. Said shaft 161 is operatively connected to the speed reducing unit 164 suitably mounted on said beams 153, and 10 with the free end of its shaft 165 carrying sprocket wheels 166 and 167, respectively. Sprocket chain 168 is adapted to connect sprocket 166 with sprocket wheel 102 mounted on one of the screw shafts 101 for driving its respective 15 screw 100, and sprocket chain 169 connects sprocket 167 with the other sprocket 102 for driving the remaining screw 100, as will be clear without further description.

Mounted on the top of frame E is the resistor 20 unit 170 with its control mechanism 171 and controller unit 172 with its rheostat 173. By means of these assemblies the speed of the driving motor 15 is determined as will be readily understood.

While the operation of the above described device would seem to be clear, yet it might be well to explain in further detail as to the composition constituting the abrasive mixture G, and the actual impregnation of the body F therewith 30 during process of being formed.

The constituency of the abrasive mixture G may be varied according to the type of abrasive stone or grindstone F desired. The hopper or mixing box 87 mounted above each of the winding assemblies 32-34-35 is adapted to contain a mortar composed of sharp crushed sandstone, flint, emery, or other abrasive, mixed with lime, or cement or other binder, or an abrasive, magnesite, chloride of magnesium and a fluid, such abrasive being delivered to the body F and the thread 33 in course of being wound thereon, and accumulates in the sump-like space 152 intermediate said body F, flanges or disks 34-35 and pressure shoe 143, and at which point it is acted 40 upon by pressure shoe 143 and imbedded in the surface of said body, and in addition to filling the interstices between the threads thoroughly 45 impregnating the threads themselves. The manner of winding the thread, through the instrumentality of the comb mechanisms, from side to side of the body in alternate opposite inclined directions relative to the axis of the body or wheel effects an interwoven fibrous structure impregnated throughout with an abrasive substance 50 under continuous side pressure and surface pressure at right angles thereto, and by virtue of which, a composite abrasive structure or grindstone F is produced.

In conclusion it will be noted that by virtue 60 of the comb mechanism C, threads of different sizes or textures may be directed to the body being formed extending in course of winding from each side, respectively, to approximately the center of the surface of said body to present a variable degree of quality across the thickness 65 so that while one side may be adapted to rapid cutting and in consequence relatively brittle, the other side may have the requisite strength. This also may be effected by the threads or strands of fibrous material being arranged in variable spaced longitudinal relation to the axis of the body, the abrasive substance being applied as hereinbefore described.

In some instances it may be desirable, instead 70 75

5 of a single strand or plurality of strands of fibrous material, to use a webbing corresponding to the desired width of the stone to be formed, and in which case the webbing is wound, treated to an abrasive mixture and completed in the same manner as heretofore described.

From the above it will be apparent that I have provided a simple, inexpensive method and apparatus for producing grinding or abrasive bodies 10 from a fibrous material so impregnated with an abrasive and adhesive mixture as to present when the same had hardened a grinding or polishing wheel or grindstone of great durability, constructed at a minimum cost and efficient for the 15 purposes intended.

Although in practice I have found that the form of my invention illustrated in the accompanying drawings and referred to in the above description as the preferred embodiment, is the 20 most efficient and practical; yet realizing the conditions concurrent with the adoption of my invention will necessarily vary, I desire to emphasize that various minor changes in details of construction, proportion and arrangement of 25 parts, may be resorted to within the scope of the appended claims without departing from or sacrificing any of the principles of this invention.

Having thus described my invention, what I desire protected by Letters Patent is as set forth 30 in the following claims:

1. A machine for forming a grindstone body from fibrous material and an abrasive substance, comprising a thread winding mechanism including pressure disks between which the thread is 35 wound to form said body, a comb element for directing the threads to the winding mechanism, a link means adapted to adjustably support the comb with respect to said body, a rack and pinion mechanism adapted to effect reciprocation of the 40 comb with respect to the winding mechanism, and means for controlling the reciprocatory action of said rack mechanism.

2. A machine for forming a grindstone body from fibrous material and an abrasive substance, 45 comprising a thread winding mechanism including pressure disks between which the thread is wound to form said body, a comb element for directing the threads to the winding mechanism, including a reciprocating bar mechanism, a sup- 50 porting mechanism carried by said bar adapted to adjustably support the comb with respect to the said winding mechanism, means for reciprocating said bar, means for controlling the reciprocating movement of the bar, and adjustable 55 pressure mechanism adapted to engage said body and maintain a predetermined constant pressure thereon during its building up process, and driving means for effecting simultaneous and positive operation of the thread winding mechanism, 60 bar reciprocating means, and pressure mechanism.

3. A machine for producing a combined polishing and cutting wheel from fibrous material and an abrasive substance comprising a thread wind- 65 ing mechanism including pressure disks, means for delivering the abrasive substance to said wind- ing mechanism, and pressure means for impreg- nating and embedding the abrasive substance into the thread being wound, said means including a

screw driven slidable supporting block, a pressure frame carried by said block, a body engaging pressure plate detachably carried by the frame, means carried by said block movable into and out of threaded engagement with said screw at any 5 point throughout its length, and driving means for effecting the simultaneous and synchronous operation of the thread winding mechanism and pressure means.

4. A machine for producing a grindstone body 10 from fibrous material and an abrasive substance comprising a thread winding mechanism includ- ing pressure disks, means for delivering the abra- sive substance to said winding mechanism, and pressure means including a screw controlled 15 sub-block for impregnating and embedding said sub- stance into the thread being wound, a pressure plate structure carried by said block and adapted to engage said body, means carried by said block normally engageable with the threads of said 20 screw and operable to permit slidable adjustment of the block with respect to the screw, means co- acting with said block to effect lateral adjust- ment of the pressure plate structure with respect 25 to said disks, and driving means for effecting si- multaneous and synchronous operation of the thread winding and pressure means, whereby a predetermined pressure on said body by the pres- 30 sure means is maintained constant during its building up process.

5. A machine for producing a grindstone body from fibrous material and an abrasive substance comprising a thread winding mechanism includ- ing pressure disks, a comb element for directing the threads to the winding mechanism, a slidable 35 bar connected to said comb, a rotatable disk co- acting with said bar to impart reciprocating movement to the comb, means for delivering the abrasive substance to the winding mechanism, and pressure means for impregnating and embed- 40 ding the abrasive substance progressively into said body, said pressure means including a screw driven supporting block, a pressure plate support- ing structure carried by the block adapted to en- 45 gage the grindstone body, and driving means 45 adapted to simultaneously and synchronously operate the thread winding mechanism, comb ele- ment, and pressure means.

6. A machine for producing a grindstone body from fibrous material and an abrasive substance 50 comprising a thread winding mechanism includ- ing pressure disks, means for delivering the abra- sive substance to said winding mechanism, and pressure means for progressively embedding the abrasive substance into the thread being wound, 55 said pressure means including a supporting frame having a detachable pressure plate engageable with said body, a slidable block structure sup- porting said frame, a driving screw, means car- 60 ried by said block engageable with the screw and operable to effect longitudinal adjustment of the block with respect to the screw and move said plate into a predetermined pressure engagement with said body, additional means for adjusting said pressure plate laterally with respect to said 65 body, and driving means adapted to simultane- ously and positively operate said winding mecha- nism and pressure means.

WALTER S. RAE.
